UNITED STATES PATENT OFFICE

134,919

DESIGN FOR AN APPLIQUE OR SIMILAR ARTICLE

Everett J. Miller, Hartford, Conn., assignor to Colt's Patent Fire Arms Manufacturing Company, Hartford, Conn., a corporation of Connecticut

Application October 12, 1942, Serial No. 108,508

Term of patent 3½ years

To all whom it may concern:

Be it known that I, Everett J. Miller, a citizen of the United States, residing at Hartford, in the county of Hartford and State of Connecticut, have invented a new, original, and ornamental Design for an Applique or Similar Article, of which the following is a specification, reference being had to the accompanying drawing, forming part thereof.

In the drawing:

Fig. 1 is a plan view of an applique or similar article embodying my new design.

Fig. 2 is a side view thereof.

The stippled and unstippled portions of the drawing are intended to represent different colors, but not any particular colors.

While the new design has been shown embodied in an applique, it is understood that the same may be embodied in other similar articles without departing from the spirit of the invention.

I claim:

The ornamental design for an applique or similar article, as shown and described.

EVERETT J. MILLER.
